UNITED STATES PATENT OFFICE.

HOLGER VARDER, OF NEW YORK, N. Y.

TRAIN-BUMPER.

1,318,033.

Specification of Letters Patent. Patented Oct. 7, 1919.

Application filed February 17, 1919. Serial No. 277,445.

To all whom it may concern:

Be it known that I, HOLGER VARDER, a citizen of the United States, residing in the borough of Manhattan, in the city of New York and State of New York, have invented 5 certain new and useful Improvements in Train-Bumpers, of which the following is a specification.

This invention relates to car bumpers or buffers for use in terminals, or on sidings, or similar positions where it is desired to bring a car or a train of cars to a standstill without leaving the tracks, and in a short distance and without a sudden shock.

Great difficulty has heretofore been encountered in providing a satisfactory device of this kind. It is of frequent occurrence that the car or train either carries away the bumper or passes over the same, sometimes with serious injury to the car, and loss of life.

According to this invention, a means is provided for surely, easily, and certainly bringing the car or train to a standstill without injury to the car or train, and also the bumper. This result is accomplished by frictional resistance which is brought into opposition to the movement of the car.

The objects of this invention are accomplished by the means illustrated in the accompanying drawings, in which:

Figure 1, is a side elevation of the improved bumper.

Fig. 2, is a plan view of the same.

Fig. 3, is a transverse section taken on the line 3—3 of Fig. 1.

Fig. 4, is a longitudinal vertical section through the top of one of the retarding members.

Fig. 5, is a horizontal section on the line 5—5 of Fig. 4.

Fig. 6, is a view of one of the roller boxes, and

Fig. 7, is a view of a modified form of bumper.

Similar reference numerals in all of the figures of the drawings designate like parts.

Referring to the drawing, 5 designates the terminal of the train track, beyond which is constructed the improved bumper which is preferably supported upon a substantial foundation formed of grillage beams 6 embedded below the surface and extending beneath the bumper and partly under the track terminal.

The bumper proper consists of a buffer-frame or arm 7 which is mounted upon one or more I-beams forming tracks 8, and constructed to move longitudinally thereof, said I-beams or tracks being rigidly secured to, and supported upon the grillage beam foundation 6 before mentioned in any suitable manner. The buffer-frame 7 is provided at its rear side with a plurality of ears 9, 65 between each pair of which is connected by the bolt 10, a retarding or resisting member 11, the same being constructed to engage the track surfaces of the I-beams 8 and adapted to move longitudinally thereof together with the buffer-frame 7. The retarding members 11 have depending, forwardly extending sides 12 located upon opposite sides of the I-beams 8, and are connected together at their lower ends, as shown 70 at 13 in Fig. 3 of the drawing. Therefore it will be seen that each of these retarding members forms a loop surrounding its respective I-beam track, and is thereby positively guided in its back and forth movements. At the upper end of each of the retarding members, is also provided a connecting piece 14 which is formed with a concave engaging face 15 adapted to contact with an oppositely concaved face 16 formed 80 between the ears 9 of the buffer-frame, and also adjacent the lower end of each retarding member, are suitably secured a group of friction-plates 17 which extend from one side of the retarding member to its opposite 90 side, as clearly shown in Fig. 3 of the drawing. In other words, these frictional plates 17 extend transversely of the space between the sides of each of the retarding members and beneath the I-beam tracks 8.

These friction plates 17 are adapted to frictionally engage a group of frictional tracks 18 positioned to extend longitudinally beneath the I-beam tracks 8, and are rigidly secured in position at one end to the 95 car-tracks by bolts or otherwise, as shown at 19', and at their other ends 19, they are preferably secured loosely to permit a slight vertical movement. These friction plates 17 and friction-tracks 18 are arranged in alternate relation to each other, so as to provide a plurality of frictional contact faces or areas, and to secure a maximum resisting force to the movement of the cars or train to be stopped.

Preferably the retarding members are normally supported upon the tracks 8 by the

rollers 20, and said rollers 20 form fulcrum points upon which the retarding members rock or tilt when they are moved along the tracks 8 on the working stroke, this tilting movement being effected by the force imposed upon the buffer-frame and through the contacting concave faces 15 and 16. The slight tilting of the retarding members causes the friction plates 17 to bear firmly 10 against the frictional tracks 18, and thereby create a resistance to overcome the movement of the body to be stopped.

For high pressure, as in the present case, it is found that the coefficient of friction 15 cannot be considered constant, in that, it changes considerably with the condition of the contacting surfaces, whether they are wet, dry or rusty, therefore the variability of the coefficient of friction has to be taken 20 into account to make the bumper practical.

To allow for a considerable variation in coefficient, rollers 20 in the retarding members are mounted in boxes 32, which in turn are mounted between vertical guides 33 projecting inwardly from the sides of the retarding members. Boxes 32 are formed with a cross rib or fulcrum edge 34 which bears against a lever 35 intermediate its ends, said lever having one end engaging under a 25 shoulder 36 formed on the housing of the retarding member, and has its other end contacting with a spring-cushioning means 37 whose tension or height can be adjusted by the wedges 38 and screw 39.

35 In operation, when the retarding members tilt, roller boxes 32 press on their levers 35 and deflect the same, and when the deflection is big enough, a positive pressure-roller 20' in each of the retarding members, is brought 40 into contact with the I-beam track. The greater the pressure due to the tilting tendency, the greater will be the pressure on rollers 20', while the pressure on rollers 20 will never exceed a certain limit determined 45 by the flexibility of the spring-cushioning means 37. Consequently the greater the combined pressure on rollers 20 and 20', the resultant pressure will be closer to roller 20', and therefore the leverage line k will be 50 greater. A great coefficient of friction needs a long leverage line k or the bumper will get stuck, and a small coefficient of friction needs a short leverage line k , else the bumper will have a resistance too small. It 55 will thus be seen that in the arrangement described, leverage line k will be adjusted automatically relative to the coefficient of friction.

An initial force resisting means, such as 60 counterweights, springs, or other like means, which are independent of the friction resistance means, is absolutely essential to perfect the operation of the bumper. The initial force resisting means shown in the drawings, 65 comprises counterweights 24 having buffer-

springs 25 and connected to the lower ends of the retarding members, and springs 26 mounted in the end of the buffer arm 7. These initial force resisting means counteract the pressure from the train, and cause 70 the retarding members to tilt and thus press the plates 17 and the tracks 18 tightly together; friction will then be developed to further counteract the force imposed by the train, and the greater the frictional force, 75 the more the retarding members will tilt, and the friction plates and tracks will be forced closer together, until a degree of friction is established which will balance with the applied force. 80

It should be further mentioned, that the initial force resisting means will act to return the bumper to its normal starting position, after the train force has been withdrawn, and as there is no frictional resistance offered on the return stroke, because no tilting force is applied at that time, the parts will move easily to normal position. 85

To overcome backward tilting of the retarding members due to the weight of their 90 lower ends, hangers 40 are provided on the bumper-arm 7, and springs 41 are connected to said hangers and the lower ends of the retarding members.

These springs are strong enough to normally uphold the lower ends of the retarding members, so that the friction plates and tracks are substantially free from engagement with each other so that no appreciable friction will be developed when in this position. 95

The bumper-frame or arm 7 is preferably supported on the tracks 8 by the rollers 27 and 28, said rollers being mounted in suitable brackets 29 secured to the member 7, 105 and the brackets which support the rollers 28 are formed with rear walls 30 which are provided at their lower ends with outwardly extending lips 31 which are adapted to engage beneath the flanges of the tracks 8, and thereby prevent an upward displacement of the bumper-arm from the tracks 8. 110

For inexpensive bumpers with a short stroke, the device can be constructed as shown in Fig. 7 of the drawings, wherein the friction rails extend upwardly and backwardly in a different horizontal plane from the level of the train-track rails. 115

Slidably mounted on each beam-track 8 is a wedge-block 45 which normally rests under the wheel 20', in the position shown in Fig. 4 of the drawings. In this position it will be seen that very little or no compression of the spring 37 is required to make the roller 20' bear on the wedge-block. As 120 the roller moves down the incline an increased pressure of spring 37 is required, as the resistance of the bumper is a coefficient times the force compressing spring 37. By this arrangement, the bumper will start with 125 130

very little resistance and gradually develop the full resistance during its movement over the length of the wedge.

The wedge is moved back and forth by the offsets 46 and 47 formed on the retarding member; thus after the retarding member moves backwardly some distance, offsets 47 will engage the head of the wedge and slide it backwardly, thereby keeping it in advance 10 of the roller 20, and then when the load is released from the retarding member and during its return stroke, offsets 46 engage the head of the wedge and return it to normal position.

Having thus fully described the invention, what is claimed is:—

1. In a train-bumper, separate groups of friction-members fixed respectively to the train-track and a movable member, said friction members of the separate groups being alternately arranged with respect to each other and mounted to be pressed together by the movement of said movable member.

2. In a train-bumper, separate groups of friction-members arranged transversely relative to each other and fixed respectively to the train-track and to a movable member, said friction members of the separate groups being alternately arranged with respect to each other and mounted to be pressed together by the movement of said movable member.

3. In a train-bumper, separate groups of friction-members fixed respectively to the train-track and to tiltable and movable members, said friction members of the separate groups being alternately arranged with respect to each other and mounted to be pressed together by the tilting movement 40 of said movable members.

4. In a train-bumper, separate groups of friction-members fixed respectively to the train-track and to movable members, said friction members being mounted to be 45 pressed together and toward fixed parts of the bumper by the tilting movement produced by the pressure of the train on the bumper, and by a force acting against the pressure of the train and at some distance 50 from the same.

5. A train-bumper, comprising a bumper-arm, retarding members connected to said arm to tilt or rock with respect thereto, tracks for supporting both said bumper-arm and retarding-members and on which they 55 are adapted to move, separate friction means fixed to said bumper and the train-track respectively and mounted to frictionally en-

gage each other with variable pressure produced by the force imposed upon the movable bumper.

6. A train-bumper, comprising a bumper-arm, retarding members connected to said arm to tilt or rock with respect thereto, tracks for supporting said bumper-arm and retarding members, said retarding members being provided with rolling supports which 65 form fulcrums upon which the retarding members are tilted, separate friction means fixed to said bumper and the train-tracks 70 respectively and mounted to frictionally engage each other with variable pressure produced by the force imposed upon the movable bumper.

7. A train-bumper, comprising a bumper-arm, retarding members connected to said arm to tilt or rock with respect thereto, tracks for supporting both said bumper-arm and retarding members, said retarding members being provided with rolling supports which 75 form automatically changeable fulcrums upon which the retarding members are tilted to adjust the leverage of the tiltable retarding members with respect to the frictional resistance, separate friction 80 means fixed to said bumper and the train-tracks respectively and mounted to frictionally engage each other with a variable pressure produced by the force imposed upon the movable bumper.

8. A train-bumper, comprising a bumper-arm, retarding members connected to said arm to tilt or rock with respect thereto, tracks for supporting both said bumper-arm and retarding members, said retarding members being provided with rolling supports which 85 form fulcrums upon which the retarding members are tilted, separate friction means fixed to said bumper and the train-tracks respectively, and mounted to 90 frictionally engage each other with a variable pressure produced by the force imposed upon the movable bumper-arm, and an independent force resisting means acting on the lower end of said retarding members.

9. A train-bumper mounted upon supporting tracks and provided with separate friction members secured to the train-track and the bumper respectively, said bumper being tiltable with respect to its supporting 100 tracks and also provided with automatically shiftable fulcrums to vary the frictional resistance between the friction members.

In testimony whereof I affix my signature.

HOLGER VARDER.
